UNITED STATES PATENT OFFICE

THOMAS H. GAGEN, OF SANDUSKY, OHIO, ASSIGNOR TO THE HINDE & DAUCH PAPER COMPANY, OF SANDUSKY, OHIO, A CORPORATION OF OHIO

HANDLED BOX OR CARTON

Application filed September 12, 1932. Serial No. 632,837.

The invention relates to boxes formed of paper or corrugated paper board and it is the object of the invention to obtain a construction provided with a carrying handle and a cover normally locked in position but which permits of easy removal for inspection of or access to the contents. The invention therefore consists in the peculiar construction as hereinafter set forth.

10 In the drawing:

Figure 1 is a side elevation partly in longitudinal section of my improved box;

Figure 2 is a perspective view thereof showing one half of the cover opened;

15 Figure 3 is a cross section on line 3—3 of Figure 1;

Figure 4 is a side elevation showing the manner of engaging and disengaging the cover.

20 The body of the box A may be formed of any suitable construction but as shown comprises bottom, sides and ends, the latter being provided with a downturned flap A' on the inside of flaps A² extending inward from the sides thereby making a three-ply thickness. The box may be formed either of solid stock or cellular double faced corrugated board, but for simplicity in illustration, I have shown the solid stock.

30 To form a cover and also a carrying handle for the box, a suitable blank B is folded at the center to form the handle section C and oppositely extending cover sections D and D', each provided with down-turned side flaps E.

35 Each of the side flaps is slotted longitudinally at its inner end as indicated at F to form tongues G which are slidably engageable with keepers H on the opposite sides of the box body A. As specifically shown, the keepers

40 H are formed by a strip which is bent into U form with its parallel sides extending through slots I and I' in the sides of the body and then respectively bent upward and downward to form securing flaps H', H² which

45 are riveted or otherwise secured to the body. This results in the forming of an external loop shaped keeper for receiving the tongues G on the cover flaps E.

50 With the construction as described, the opposite sides of the fold which forms the han-

dle are spread apart as indicated in Fig. 4 which permits of inserting the ends of the tongues G into the loop keeper H. The cover sections D and D' are then slid inward until the handle fold is closed, in which position 55 the tongues G will lock each of the cover sections to the body. However, the cover may be removed at any time, either on one or both sides, by sliding one or both sections outward so as to disengage the tongues G. The handle 60 C has an aperture C' cut in the lower portion thereof for forming a hand hold.

A box constructed as described forms a very convenient carrier for fruits and vegetables, and one which permits the quick inspection 65 but nevertheless effectively protects the contents.

What I claim as my invention is:

1. The combination with a box body having an open top, of a cover for said box comprising two portions connected by an intermediate folded portion extending transversely therefrom, a keeper on said box body and oppositely extending tongues on said cover portions insertable into said keeper upon the opening of said folded portion and slidable into locking engagement therewith upon the closing of said folded portion.

2. The combination with a box body having an open top, of a cover for said box body having two portions connected by an intermediate folded portion extending transversely therefrom, said cover portions being provided with downturned flaps adjacent to one side of said box with tongues projecting oppositely therefrom, and a keeper on the side of the box body with which said tongues can be initially engaged upon the opening of said folded portion whereby the closing of said folded portion will effect a full engagement of said tongues with said keeper to lock said cover sections to the box body.

3. The combination with a box body having an open top, of a combined cover and handle for said box body comprising two portions connected by an intermediate folded portion, the latter being slotted for a hand hold, flaps on said cover sections extending adjacent to a side of said box body

and having oppositely projecting tongues, and a keeper on said box body with which said tongues can be initially engaged upon the opening of said folded portion, whereby the closing of said folded portion will effect the locking of said cover portions to the box body.

4. The combination with a box body having an open top, of a combined cover and handle for said box body comprising two portions connected by an intermediate folded portion extending transversely therefrom, said folded portion being partially cut away for a hand hold, flaps on opposite sides of each of said cover portions extending adjacent to the sides of said body portion, said flaps having tongues projecting oppositely from the two portions and keepers on opposite sides of said box to which said tongues can be initially engaged upon the opening of said folded portion whereby the closing of said folded portion will lock said cover sections and flaps to said box body.

5. The combination with a box body having an open top, of a combined cover and handle for said box body comprising two portions connected by an intermediate folded portion extending transversely therefrom and slotted for a hand hold, said cover portions being each provided with depending flaps adjacent to the sides of said box body.

and being slotted to form projecting tongues and loop shaped covers attached to opposite sides of said box body with which said tongues can be initially engaged upon the opening of said folded portion whereby the closing of said folded portion will lock said cover section and flaps to said box body.

6. The combination with a box body having an open top, of a combined cover and handle for said box body comprising two portions connected by an intermediate folded portion extending transversely therefrom and being slotted for a hand hold, said portions being each provided with depending flaps adjacent to the opposite sides of said box body and slotted to form oppositely projecting tongues, and loop shaped keepers on said box body formed by U-shaped strips extending through slots in the sides of the box body with oppositely turned flanges secured to the inner face of the side of said box body, said keepers being adapted for the initial engagement of said tongues upon the opening of said folded portion whereby the closing of said folded portion will slide said tongues into full engagement with said loop-shaped keepers and lock said cover and handle to the box body.

In testimony whereof I affix my signature.

THOS. H. GAGEN.
